CARBURETOR

Marion Mallory, Detroit, Mich.

Application July 3, 1934, Serial No. 733,665

8 Claims. (Cl. 261—46)

This invention relates to carburetors and more especially to the means for controlling the primary fuel mixture which is supplied to the passageway leading to the intake manifold.

In the type of carburetor to which the invention relates, the fuel charge first mingles with a comparatively small air stream and is then drawn centrally into the main air stream which flows to the intake manifold. The primary object of the invention is to provide improved means for regulating the fuel charge in its relation to the throttle opening. This regulation is effected, in the present instance, by controlling the flow of air into and through the chamber within which the primary mixture takes place. The invention also is easily adapted to thermostatic regulation of the mixture until the engine is warmed up.

The means by which the above objects are attained will be more particularly described in connection with the accompanying drawings, in which,—

Figure 1 is a central vertical section taken through the air intake passageway and the float chamber of a carburetor constructed according to the invention.

Figure 2 is a section taken on the line 2—2 of Figure 1.

Figure 3 is a view similar to Figure 1, illustrating a modification.

Figure 4 is a section taken on the line 4—4 of Figure 3.

The invention is illustrated in connection with a down draft carburetor having a main fuel passageway 10 provided with an air intake 11 and with an outlet 12, within which is a throttle valve 13. A float chamber 14 is supplied with fuel through a pipe 15 past a valve 16 which is controlled by the usual float 17, so as to maintain the fuel at a constant level within the chamber 14. From the chamber 14, fuel flows through a passageway 18 and main fuel restriction 19 into a well 20.

A bar or bridge 21 extends across the passageway 10 and has a mixing chamber in the form of a tube 22 secured thereto. This tube or chamber has air bleed holes 23, a fuel inlet 24 leading from the well 20, and an outlet 25 opening downwardly at the center of the passageway 10.

When the engine is idling, fuel is supplied from the well 20 through idling tube 26, idling fuel restriction 27 and passageway 28, where air is mixed with the fuel. The fuel mixture then issues through the idle outlet restriction 29 to the fuel intake passageway on the engine side of the throttle valve 13. Air is admitted to the passageway 28 through air inlet 30 and the amount of air thus admitted is adjusted by a screw 31.

Air flow through the passageway 10 is adapted to be restricted by valves 32 which, in the present instance, are secured to pivot pins 33, each

of which has a spring controlled crank or eccentric 34, outside of the carburetor casing, to urge the valve toward closed position.

In the construction shown in Figures 1 and 2, a venturi 35 is located above the valves 32 and the bleed holes 23 are located substantially at the choke of the venturi, so that as the air flow through the venturi increases, due to a wider opening of the throttle valve, the ratio of air to fuel in the mixing tube 22 is decreased. A sleeve 36 is slidably mounted on the tube 22 and its movement is controlled by a link 37 connecting it to a wrist pin 38 on a crank disk 39, which is secured to a shaft 40 mounted transversely to the air intake 11. A crank 41, secured to the shaft 40, is connected by a link 42 to a thermostat 43. At low temperatures, the thermostat moves the sleeve 36 upwardly to cover the holes 23. At the same time, a flange 44 on the sleeve 36 engages crank arms 45 on the hubs of the respective valves 32 and imposes an additional load tending to close them, thereby insuring a rich mixture. As the temperature rises, the thermostat lowers the sleeve 36, progressively uncovering the holes 23 and releasing the valve 32, so that the mixture is ultimately regulated by the air flow controlled by the throttle valve and the engine suction.

In the construction shown in Figures 3 and 4, the venturi is omitted and the valves 32 are connected by links 46 to a sleeve 47 which progressively covers the holes 23 to mechanically cut down the ratio of air to fuel supplied to the mixing tube 22, instead of effecting this result by the kinetic suction of the main air flow, as in the construction shown in Figures 1 and 2. The plunger 48 inside of the tube 22 and connected to the link 37, as shown in Figures 3 and 4, serves the same purpose as the sleeve 36 in Figures 1 and 2, in covering or uncovering the holes 23 in response to changes in temperature.

In air valve carburetors as heretofore constructed, the fuel supply is usually regulated by a metering pin in the main fuel orifice, but with such a construction, considerable difficulty is encountered because of the extreme accuracy required in its manufacture and because of its inability to hold its calibration under normal service conditions. In accordance with the present invention, the metering is effected by regulating the flow of air through the holes 23, either by mechanical means connected with the restrictive valves 32 or by the kinetic suction of the main air flow through the venturi 35. Regulation by this method requires far less precision than regulation by direct metering of the fuel stream, because the average mixture ratio is approximately sixteen parts of air to one of fuel.

In the operation of this invention, no metering pin is required. The amount of fuel supplied to

the engine is determined by the rate of air flow through the bleed holes 23 into the primary mixing tube 22.

In the construction shown in Figures 1 and 2, when the engine is operating at low speed, the restriction of the valves 32 causes a relatively large flow of air through the holes 23, which reduces the suction through the fuel inlet 24, thereby reducing the amount of fuel supplied to the engine. As the engine speed increases, the valves 32 open wider in response to greater suction. However, regardless of the slightly increased suction on the outlet 25, less air enters the inlets 23 than at low speed, due to the increased suction through the venturi.

In the modification shown in Figures 3 and 4, there is no venturi, but a similar regulation of the amount of air flowing into the mixing tube 22 is positively effected by mechanical means, rather than suction of the main air flow. In other words, as the restrictive valves 32 open, the air bleed holes 23 are progressively closed by the sleeve 47, which has direct link connections with the valves.

In both forms of the invention herein shown, the thermostat 43 and its connections close the bleed holes 23 when the engine is cold and progressively open them as the engine warms up.

While the construction of the primary mixing tube is particularly well adapted to be combined with thermostatic regulation, the latter may, of course, be omitted if desired. It will also be apparent that the means for regulating the fuel flow in response to variations in the flow of the main air stream may be considerably modified without departing from the scope of the appended claims.

I claim:

1. In a carburetor, the combination of a main air passageway, an air valve therein, yieldable means tending to close said valve, a primary mixing tube with one end closed and with the other end opening into said passageway on the engine side of said air valve, said tube having an air inlet and a fuel inlet, a sleeve on said tube, and means operatively connected with the air valve for moving said sleeve to progressively cover said air inlet as said air valve is opened.

2. In a carburetor, the combination of a main air passageway, a mixing chamber having an air inlet from and a mixture outlet into said passageway and having also a fuel inlet opening of constant size, a throttle valve on the engine side of said outlet, means for progressively reducing the ratio of air to fuel supplied to said chamber as the air flow through said passageway is increased, and thermostatic means independent of the air flow for reducing the supply of air to said mixing chamber at low temperatures.

3. In a carburetor, the combination of a main air passageway, an air valve therein, yieldable means tending to close said valve, a primary mixing chamber having an air inlet from said passageway on the atmospheric side of said air valve and having also a fuel inlet opening of constant size, an outlet from said chamber to said passageway on the engine side of said air valve, a throttle valve on the engine side of said outlet, means for progressively reducing the ratio of air to fuel supplied to said chamber as the throttle valve is opened, and thermostatic means effective inde-

pendently of said air valve to reduce said ratio at low temperatures.

4. In a carburetor, the combination of a main air passageway, an air valve therein, yieldable means tending to close said valve, a venturi in said passageway on the atmospheric side of said air valve, a primary mixing chamber within said passageway having an air inlet therefrom at the choke of the venturi and having also a fuel inlet opening of constant size, a throttle valve in said passageway on the engine side of said air valve, an outlet from said chamber into said passageway between the air valve and the throttle valve, whereby the suction through the venturi progressively reduces the ratio of air to fuel supplied to said chamber as the throttle valve is opened, and thermostatic means operable independently of the air suction to reduce said ratio at low temperatures.

5. In a carburetor, the combination of a main air passageway, an air valve therein, yieldable means tending to close said valve, a primary mixing chamber having a fuel inlet opening of constant size and an air inlet, an outlet from said chamber to said passageway on the engine side of said air valve, means for progressively closing the air inlet to said chamber as said air valve is opened, and thermostatic means to close said air inlet, independently of said air valve, at low temperatures.

6. In a carburetor, the combination of a main air passageway, an air valve therein, yieldable means tending to close said valve, a primary mixing tube with one end closed and with the other end opening into said passageway on the engine side of said air valve, said tube having a fuel inlet opening of constant size and an air inlet, a sleeve on said tube, means for moving said sleeve to progressively cover said air inlet as said air valve is opened, and thermostatic means independent of said sleeve to restrict said air inlet at low temperatures.

7. In a carburetor, the combination of a main air passageway, an air valve therein adapted to be opened by the air flow, yieldable means tending to close said valve, a primary mixing chamber having an air inlet and a fuel inlet opening of constant size and having an outlet into said passageway, means for utilizing the main air flow to reduce the ratio of air to fuel supplied to said primary mixing chamber as the main air flow increases, and thermostatic means operable at low temperatures to cut down the air supply to said chamber regardless of the rate of the main air flow.

8. In a carburetor, the combination of a main air passageway, an air valve therein adapted to be opened by the air flow, yieldable means tending to close said valve, a primary mixing chamber having an air inlet and a fuel inlet and having an outlet into said passageway, means for utilizing the main air flow to reduce the ratio of air to fuel supplied to said primary mixing chamber as the main air flow increases, thermostatic means operable at low temperatures to cut down the air supply to said chamber regardless of the rate of the main air flow, and means actuated by the thermostatically controlled means to positively close said air valve as the air supply to the primary mixing chamber is thus cut down.

MARION MALLORY.
